PROCESS FOR CRACKING HYDROCARBON OILS

Original Filed June 30, 1920

UNITED STATES PATENT OFFICE

GUSTAV EGLOFF, OF CHICAGO, ILLINOIS, ASSIGNOR TO UNIVERSAL OIL PRODUCTS COMPANY, OF CHICAGO, ILLINOIS, A CORPORATION OF SOUTH DAKOTA

PROCESS FOR CRACKING HYDROCARBON OILS

Application filed June 30, 1920, Serial No. 393,099. Renewed March 24, 1927.

My invention relates to a process for the pressure distillation of heavy hydrocarbon oils by means of an ascending pressure in a battery of pressure stills.

Among the salient objects of my invention are to provide a process, preferably continuous, of a battery of pressure stills, in which each succeeding still is maintained at a higher temperature and pressure than the preceding still of the battery for the purpose of cracking heavy hydrocarbon oils producing light oils therefrom; to provide a process of ascending temperatures and pressure in a battery of pressure stills and diverting the dephlegmated oil from the still in which it was generated to the next one in the battery maintained at a higher temperature and pressure than the preceding still of the battery; to provide a process of cracking hydrocarbon oils to produce light oils therefrom by means of an ascending temperature and pressure and diverting the residuum oil of one still to the next still of the battery which is maintained at a higher temperature and pressure than the preceding still of the battery; to provide a process of an ascending temperature and pressure distillation of heavy hydrocarbon oils to produce gasoline or light oils therefrom, to inject untreated hydrocarbon oil into each still of the battery maintained at a higher temperature and pressure than the preceding still of the battery; to provide a process of an ascending temperature and pressure in a battery of continuous pressure stills mixing the dephlegmated oil, residuum and untreated hydrocarbon oil and pumping the mixture to the next succeeding still of the battery maintained at a higher temperature and pressure than the preceding still of the battery; to provide a process of an ascending temperature and pressure distillation of heavy hydrocarbons to produce gasoline or light oils therefrom in which the temperature conditions are higher from still to still of the battery of pressure stills and subjecting the dephlegmated oil and residuum of the previous still to a higher temperature than the one they were subjected to in the previous still whereby the velocity of cracking is increased; to provide an apparatus of

a battery of pressure stills interconnected with one another so that the dephlegmated oil, residuum and untreated oil is pumped to the next still of the battery of high pressure stills.

The single figure of the drawing shows a view, partly perspective, and partly in elevation and partly in dotted lines, of my improved apparatus.

A description of the apparatus as per drawing is as follows:

Referring to the drawing, 1, 2, 3 and 4 are furnaces in which the burners 5, 6, 7 and 8 are placed, attached to a source of fuel supply 9, controlled by valve 10 in header line 11. High pressure stills 12, 13, 14 and 15 are set in furnaces 1, 2, 3 and 4. Vapor lines 16, 17, 18 and 19 attached to stills 12, 13, 14 and 15 are connected with dephlegmators 20, 21, 22 and 23 in which are set baffle plates 24, 25, 26 and 27. Conduits 28, 29, 30 and 31 are attached to dephlegmators 20, 21, 22 and 23 and connected with coil condensers 36, 37, 38 and 39 set within water condenser boxes 32, 33, 34 and 35. Pressure gauges 40, 41, 42 and 43 are connected with receivers 44, 45, 46 and 47.

Pressure distillate is run via pipe 48 controlled by valve 49 and connections 50 to storage tank. Similar equipment being attached to receivers 44, 45, 46. Uncondensable gas pressure control valves 51, 52, 53 and 54 are shown connected to the top of receivers 44, 45, 46 and 47. A raw oil pump 55 connected with storage tank not shown, pumps oil by way of pipe 56 controlled by valve 57 into still 12 by way of connection 58. 62, 63 and 64 are deflectors for the dephlegmated oil condensates separated from the vapors in dephlegmators 20, 21 and 22 so that the condensed liquid will pass by way of pipes 65, 66 and 67 controlled by valves 68, 69 and 70 to pumps 80, 81 and 82, which at the same time draw residuum oil out of the stills 12, 13, 14 by means of pipes 71, 72 and 73 having valves 74, 75 and 76 connected therein. At the same time raw oil is drawn from storage tank controlled by valves 77, 78 and 79, pumps in one stream dephlegmated oil, residuum and raw oil into stills 13, 14 and 15 through connec-

tions 59, 60 and 61. 83 is the final residuum draw off pipe from still 15 of the battery and is controlled by valve 84, with connection 85, which may either go to storage tank or coking still in which, by reduction of pressure, more distillate oil may be taken off the residuum, than by means of the last still in the battery of high pressure stills.

A typical mode of operation of this process 10 and apparatus is to charge stills 12, 13, 14 and 15 with relatively heavy hydrocarbon oil such as a midcontinent gas oil of 31.0° Baumé gravity by means of pumps 55, 80, 81 and 82. When the high pressure stills are charged to 15 approximately 70 percent of their capacity the uncondensable gas valves 51, 52, 53 and 54 are closed. The pressure distillate valves 50 on receivers 44, 45, 46 and 47 are also closed. Dephlegmated oil valves 68, 69 and 20 70 are closed as also are residuum valves 74, 75 and 76. Burners 5, 6, 7 and 8 are ignited and self-generated hydrocarbon vapor pressure built up on stills 12, 13, 14 and 15 to the uncondensable gas valves 51, 52, 53 and 54. 25 A typical series of liquid temperatures and pressures upon stills 12, 13, 14 and 15 when using a midcontinent gas oil of 31.0° Baumé gravity, are; upon still 12 a pressure of 80 pounds per square inch with the liquid temperature of 710 degrees F.; upon still 13, 100 pounds pressure per square inch, liquid temperature of 730 degrees F.; upon still 14, 120 pounds pressure per square inch and 750 degrees F.; and upon still 15 a pressure of 140 pounds pressure per square inch and 775 degrees F. When pressure distillation is taking place in the stills of the battery the dephlegmated oil is run back through vapor lines 16, 17, and 18, valves 68, 69 and 70 are 30 opened, as well as the residuum valves 74, 75 and 76 connected to stills 12, 13 and 14 by means of pipes 71, 72 and 73. Pumps 80, 81 and 82 are started and draw the residuum and dephlegmated oils of stills 12, 13 and 14 35 and at the same time pump untreated oil through valves 77, 78 and 79 so that the three streams of dephlegmated oil, residuum and untreated oil are pumped into stills 13, 14 and 15. 40 By this process and apparatus a typical run upon a midcontinent gas oil of 31.0° Baumé gravity produced 65 percent of a pressure distillate oil of an average gravity of 52.0° Baumé containing 62 percent of a 58.0° 45 Baumé gravity gasoline calculated on the basis of raw oil treated 40 percent of 58.0° Baumé gravity gasoline and 17 percent of 40.5° Baumé gravity kerosene.

I do not limit myself to a horizontal battery of high pressure stills in my process. I believe it comes within the scope of my invention to include a battery of vertical stills of the shell type or tubular type, and I also believe that my invention covers pipe stills 50 of either horizontal or vertical character, of

a continuous character or connected to headers.

I claim as my invention:

1. A process for cracking hydrocarbon oils to produce lighter hydrocarbons therefrom, 70 consisting in passing the oils through a series of cracking zones, the oil in the succeeding zones being subjected to a higher pressure and temperature than in the preceding zones, taking off vapors from each zone, subjecting 75 them to reflux condensing action and returning the reflux condensate with a quantity of raw oil to a cracking zone of the next increasing pressure and temperature.

2. A process for cracking hydrocarbon 80 oils to produce lighter hydrocarbons therefrom, consisting in passing the oils through a series of cracking zones, the oil in the succeeding zones being subjected to a higher pressure and temperature than in the preceding 85 zones, taking off vapors from each zone, subjecting them to reflux condensing action and returning the reflux condensate formed by the condensing action of the vapors evolved in one of said zones to a cracking zone of increasing pressure and temperature, and continuously supplying fresh oil to said cracking zones with the reflux condensate and drawing off the residue therefrom.

3. A process of cracking hydrocarbon oils, 90 consisting in passing oil through a series of stills, in maintaining a different temperature and pressure in each still, in taking off vapors from each still, in subjecting said vapors to reflux condensation, in returning the 95 reflux condensate produced from vapors generated in one still to a succeeding still of a different temperature and pressure, and in adding raw oil to the reflux condensate introduced to each still.
